UNITED STATES PATENT OFFICE

LE ROY A. PRESCOTT, OF MUSKEGON, MICHIGAN, ASSIGNOR TO BENNETT PUMPS CORPORATION, OF MUSKEGON, MICHIGAN, A CORPORATION OF MICHIGAN

ILLUMINATING DEVICE

Application filed May 31, 1929. Serial No. 367,485.

This invention relates to an illuminating mechanism adapted to be used in conjunction with measuring pumps which are used for dispensing liquids, particularly gasoline at 5 service stations.

Gasoline pumps are in most instances housed within a housing and it is desirable that said housing of the pump be equipped with an indicating card or similar device on 10 which will appear the price of gasoline, usually associated with which is a table giving the computed prices for various numbers of gallons of gasoline at such price per gallon. Gasoline pumps also in many cases have an 15 indicating dial with pointer hands operable thereover which may be set with respect to the dial at a desired quantity required by a customer and the pump is then operated and pumps the gasoline until automatically 20 stopped when the selected quantity has been pumped as indicated on the dial.

With my invention it is possible to simultaneously illuminate both the indicator giving the prices per gallon of the gasoline and the indicating dial whereby the customer may readily see both at night, and whereby it is made easy and convenient for the operator and customer to see the indicator and avoid mistakes which would otherwise be liable to 25 occur; and with my invention a single illuminating device serves the purpose of fully and completely illuminating both indicators.

It is an object and purpose of the present invention to provide a pump with illuminating mechanism by means of which the advantage enumerated may be efficiently and economically attained.

An understanding of the invention may be 30 had from the following description taken in connection with the accompanying drawing, in which,

Fig. 1 is a fragmentary vertical section substantially on the plane of line 1—1 of Fig. 2.

Fig. 2 is a front elevation of the upper part

of a gasoline pump casing equipped with my invention, and

Fig. 3 is a rear elevation of the partial ring element which is located around the sides and lower portion of the indicating dial.

Like reference characters refer to like parts in the different figures in the drawing.

The pump casing 1 is of sheet metal enclosing the pump mechanism and ordinarily at its upper end is equipped with a closing head 2. It has an opening 3, at what may be termed 50 its front side, located near the upper end of the casing around which is a retaining frame 4 for holding a glass plate 5 and an indicating card 6 back of the plate, as shown in Fig. 1, on which the figures for the price per gallon of gasoline and the table for various quantities at such price are printed. The indicating card 6 may be removed and replaced by a different card should the price per 55 gallon change as frequently occurs.

Below the indicating card assembly a circular opening 7 is made in the casing 1 around which is a circular clamping or retaining ring 8 for securing a glass plate 9 and a partial ring member in place. The ring member consists of an upwardly and inwardly extending flange 10 at its outer edges formed with an integral vertical flange 11 which lies between the clamping ring 8 and the outer side of the 60 housing around the opening 7 except at the upper portion where a segment of the ring is removed making a relatively wide opening, indicated at 12.

The dial 13 is a circular dial on which a 65 consecutive series of numbers is printed adjacent the edges of the dial. The dial is secured at the end of a supporting bracket 14 and is of a size to fit snugly within the upwardly and inwardly extending flange 10 as 70 shown in Fig. 1.

Indicating hands 15 are mounted on a suitable shaft 14^a which extends through the bracket 14, and in practice, extends through the opposite side of the housing and through 75 80 85 90

a similar dial and cover plate 9, this being for the purpose of permitting the operator to turn the shaft to set the hands 15 at a quantity of gasoline which may be wanted by a customer.

5 Within and under the head 2, and in practice supported thereby, is a hollow arm 16 which terminates in an enlargement for receiving an electric light socket 17 in which a light bulb 18 may be carried directly back 10 of the indicating card 6, it being evident that the wires leading to the socket 17 pass through the hollow arm 16. A reflector 19 is attached to the lower end of the arm 16 and is curved around the sides and back of the light bulb 18.

15 When the light is lit the rays of light shine through the indicating card 6, which may be transparent or partially transparent, the figures marked on the card being completely 20 opaque so that the same will show up prominently. The rays also pass downwardly through the opening at 12 in the ring member around the indicator 13 and illuminate the face of the dial 13 so that it may be very 25 distinctly seen. The customer buying the gasoline is able to check both the amount for which he asks and the price he must pay therefor, both indicators being completely 30 and fully illuminated so that this may be easily done, which previously, particularly at night, was more or less difficult.

The construction while of a simple character is one of merit and very advantageous in conjunction with dispensing pumps for 35 liquids such as gasoline or the like. The invention is defined in the appended claims and is to be considered comprehensive of all forms of structure coming within their scope.

I claim:

40 1. In a device of the class described, a vertical pump enclosing housing having two openings therein, one below the other, in the same side of the housing, an indicating card secured at the upper of said openings, a dial and indicating hands movable thereover, a 45 short distance within the housing back of the lower opening, a ring member having an inwardly extending flange and a vertical flange and having a section including both 50 flanges removed at its upper side extending through said lower opening, the vertical flange bearing against the outer side of the housing and the inwardly extending flange extending to and passing around the sides 55 and lower portion of said dial, means for securing said ring member in place, and an electric light located within the housing back of said upper opening and directly above the open upper side of said ring member.

60 2. In a construction of the class described, an enclosing sheet metal pump housing having two openings, one located above the other in the same side of the housing, the upper opening being adapted to have an indicating 65 card secured thereover, a dial mounted with-

in the housing back of the lower opening, a ring member surrounding the sides and lower portion of the dial and having an open section at its upper side, and a light located back of the upper opening on the housing 70 whereby its rays may be directed therethrough and also downwardly in the opening at the upper side of said ring member to the face of the dial.

75 In testimony whereof I affix my signature.

LE ROY A. PRESCOTT.
